UNITED STATES PATENT OFFICE.

MOSES ALIBER, OF DES MOINES, IOWA, ASSIGNOR OF ONE-FOURTH TO EDWARD D. LEWIS,
OF CHICAGO, ILLINOIS.

BOTTLE-STOPPER.

No. 921,055.

Specification of Letters Patent.

Patented May 11, 1909.

Application filed June 10, 1908. Serial No. 437,684.

To all whom it may concern:

Be it known that I, MOSES ALIBER, a citizen of the United States of America, and resident of Des Moines, Polk county, Iowa, have invented a new and useful Bottle-Stopper, of which the following is a specification.

The object of this invention is to improve the construction of bottle stoppers and to enable a metallic sealing cap to be removed readily from the neck of a bottle without the use of an instrument and without damaging the cap.

A further object of this invention is to provide an improved construction for sealing caps adapted to be removed and replaced relative to the neck of a bottle without the use of an instrument.

My invention consists in the construction, arrangement and combination of elements hereinafter set forth, pointed out in my claim and illustrated by the accompanying drawing, in which—

Figure 1 is a plan of a blank from which my improved sealing cap is made. Fig. 2 is a plan of the complete sealing cap. Fig. 3 is a vertical section illustrating the sealing cap in position on the neck of a bottle. Fig. 4 is a side elevation illustrating the sealing cap in position on the neck of a bottle. Fig. 5 is a cross-section on the indicated line 5—5 of Fig. 4.

In the construction of the device as shown the numeral 10 designates a sealing cap constructed of sheet metal and formed with a locking flange 11 adapted to engage an annular shoulder 12 of the neck 13 of a bottle. The locking flange 11 is adapted to be crimped or bent into locking contact with the shoulder 12. A sealing disk 14, of any suitable material such as cork, is mounted in the sealing cap 10. The bending and crimping of the locking flange 11 is effected while the sealing disk is under pressure and an instrument and the exertion of considerable force ordinarily would be necessary in order to remove the stopper from the bottle. To enable the stopper to be removed readily from the bottle, without employing an instrument, the cap is formed at one side with an integral strip or tongue 15, which diverges near to and joins the margin of the locking flange 11. The strip or tongue 15 is of materially greater width at its inner end than at its outer end and is curved outwardly below its juncture with the locking flange 11. The strip or

tongue 15 is provided with inturned side margins 16, 17 and is crimped coincident with the flange 11 to strengthen it, and a hole 18 is formed in the outer end of said tongue to receive a ring 19. The ring 19 may be omitted if desired. The blank from which the cap 10 is constructed is shown in Fig. 1 and the marginal portions 16, 17 are shown extended as they appear before being turned inward to stiffen or strengthen the tongue. 65

The sealing cap 10 with the sealing disk 14 is applied to a filled bottle and effectively crimped and contracted thereon as shown in Figs. 3 and 4. When it is desired to open the bottle manual force is applied to the tongue 15 (or to the ring 19) to such extent as may be necessary to lift the cap 10 away from the bottle; the lifting force acting to spring the side of the flange 11 integral with the base of the tongue away from the annular shoulder 12 of the neck 13 of the bottle. Any desired portion of the contents of the bottle, or all of such contents, may be removed and, thereafter, the cap may be replaced on the bottle by a movement of the cap and tongue 70 75 80 the reverse of the movement described to open the bottle.

Heretofore sealing caps have been adapted for removal by an instrument extraneous to the cap; and also by being torn or broken 85 and rendered unfit for further use; but it will be observed that my improved cap may be removed and replaced as desired without any damage to the cap. The use of the ring 19 is desirable when the cap is employed as a 90 stopper for a bottle containing effervescent liquid, such as beer, since in such use it is necessary to apply the cap more firmly to the neck of the bottle and more force is required to remove it. 95

In order to manufacture a stopper of this class, it is essential that the cap and the lever be formed integral from a single piece of sheet metal. Experience has proven that the most satisfactory results in stoppers of 100 this kind are attained by the use of a cap having its margins extended inwardly at its lower edge, to fit around underneath the flange 12 of a bottle, and that this must be done all around the entire circumference of the cap. In order therefore to provide a lever or handle at one side of the cap there must be a sharp bend made at the point where the lower edge of the cap merges into the upper end of the lever, as clearly shown 105 110

in Fig. 3 of the drawings. Furthermore, in order that the lever may have sufficient rigidity to accomplish the function for which it is intended, and at the same time be made out of the same material as the cap, the material must be reinforced and strengthened at the point where the lower edge of the cap merges into the lever. In forming caps of this kind without levers, it has been customary to provide reinforcing corrugations all around the flange of the cap. I have provided for reinforcing the lever at the point named, by providing corrugations in the metal itself extending from the flange of the cap into the lever, past the point where the cap and the lever come together, and by this structure, I provide a cap in which the margins all around the periphery are fitted under the flange of the bottle, and the lever is offset from the margin of the cap, and at the same time the lever and cap at the juncture thereof are made strong and rigid, notwithstanding the fact that the same material of which the cap is formed is used for the lever.

25 The lever is further strengthened and reinforced at the upper end by being curved in the same manner as the cap.

I claim as my invention—

An improved bottle stopper, formed of a single piece of sheet metal and comprising a top to extend over the mouth of a bottle,

and sides extended downwardly and then inwardly around the entire circumference of the stopper to engage a rib around the mouth of a bottle, the lower edge of said sides being extended outwardly around the entire circumference of the stopper, said parts being so arranged that the stopper may be forced upwardly from a bottle at one point and said sides will spring outwardly away from the rib on the bottle, said stopper also being provided with a lever or handle formed integral with the stopper and extended from the outwardly projecting lower edge of the sides downwardly in a direction substantially at right-angles to the top, said lever having its upper end portion, that is adjacent to the top, segmental in cross section to thereby strengthen and reinforce it at the point where it unites with the outwardly projecting flange at the lower end of the cap, and said cap and flange both being provided with reinforcing corrugations, said corrugations on the lever being extended over the point where the lever unites with the outwardly projecting lower edge of the sides.

Signed by me at Des Moines, Iowa, this tenth day of February, 1908.

MOSES ALIBER.
